CLAIM

The ornamental design for a motorcycle tire, as shown and described.

DESCRIPTION

FIG. 1 is a perspective view of a motorcycle tire showing my new design;

FIG. 2 is a front view thereof, the back view being a mirror image thereof;

FIG. 3 is a top view thereof, the bottom view being identical;

FIG. 4 is a right side view thereof;

FIG. 5 is a left side view thereof;

FIG. 6 is a fragmentary enlarged front view; and,

FIG. 7 is an end view taken along line 7-7 in FIG. 6.

Broken lines show environmental portions of a tire that are not being claimed, and form no part of the claimed design. The light stippled surface shading represents the surface of the tire tread, and the dark stippled surface shading represents the recessed portion of the tread grooves, having the depth as shown in FIG. 7.
